COMBINED FOLDING CHAIR, TACKLE BOX AND ICE CHEST

Albert Sokolis, 302 Ben Drive, Chatham, Ill.

Filed July 30, 1964, Ser. No. 81,075

Term of patent 14 years

(Cl. D15—1)

FIGURE 1 is a perspective view from the front of a combined folding chair, tackle box and ice chest showing my new design, the back rest being in extended position, side opposite to that shown being the same, and

I claim:

The ornamental design for a combined folding chair, tackle box and ice chest, as shown and described.
